E. F. NORTHRUP.
ARTIFICIALLY COOLED HIGH FREQUENCY COIL.
APPLICATION FILED APR. 18, 1919.

1,328,336.

Patented Jan. 20, 1920.

UNITED STATES PATENT OFFICE.

EDWIN F. NORTHRUP, OF PRINCETON, NEW JERSEY, ASSIGNOR TO THE AJAX METAL COMPANY, OF PHILADELPHIA, PENNSYLVANIA, A CORPORATION OF PENNSYLVANIA.

ARTIFICIALLY-COOLED HIGH-FREQUENCY COIL.

1,328,336.

Specification of Letters Patent. Patented Jan. 20, 1920.

Application filed April 18, 1919. Serial No. 291,161.

To all whom it may concern:

Be it known that I, EDWIN F. NORTHRUP, a citizen of the United States, residing at 30 Wiggins street, Princeton, in the county 5 of Mercer and State of New Jersey, have invented a certain new and useful Artificially-Cooled High-Frequency Coil, of which the following is a specification.

My invention relates to high frequency 10 induction heating apparatus well illustrated by electric furnaces.

The purpose of my invention is to artificially cool an induction coil carrying high frequency current in order to maintain the 15 coil at a low temperature and correspondingly low resistance, to increase the current-carrying capacity and improve the insulation.

A further purpose is to produce the materials described and similar materials and to use the methods by which they are produced.

My Patents, Nos. 1,286,394 and 1,286,395 both of December 3, 1918, as well as several 25 pending applications, are directed to the utilization of high frequency electric current in the inductive transfer of heat, presenting various arrangements and constructions among the many by which this 30 result may be attained.

By artificially cooling the inductor coil, I have found that there is practically no limit to the temperature which can be attained, without necessity for interlinkage of transformer iron and with any special conditions desired,—including carbon free treatment and melting, and application of a vacuum. The artificial cooling is of benefit in improving the efficiency of high frequency 40 inductive heating even where high temperatures are not required.

The turns of the coil may safely be wrapped much closer together and the coil itself may be placed closer to the resistor heated, without increase of coil resistance 45 by reason of temperature rise and without danger of short-circuiting between the turns of the coil or between the coil and the other apparatus by reason of ionization of the 50 air about the coil.

The artificial cooling of the coil makes possible also the use of other insulations or dielectrics, without consequent over-heating from the closing of this space about the 55 coil. The insulation can be chosen without

regard to its capacity to stand heat as it can be maintained at room temperature if desired.

Recognizing that this invention is applicable to any kind, form or shape of high frequency coil, to which the high frequency current is applied by any means whatever, and with any form of artificial cooling, I have selected for illustration the simplest form of current supply, paralleling Figure 65 1 of each of my two patents above indicated, have applied the high frequency current to an extremely simple form of inductor furnace and have utilized water-cooling of the coil.

Fig. 1 is a diagrammatic view showing a simple form of high frequency current supply.

Fig. 2 is a vertical central section of a form of furnace to which my invention is applied.

Fig. 3 is a broken section of a modified form.

Similar numerals indicate like parts in the drawings.

The single phase alternating current line terminals A, N are shown as charging a capacity C through a heating coil O. The gap provides for discharge of the capacity C through the coil. The inductance and resistance of the coil circuit are indicated diagrammatically by L¹, L², R¹, R², and the inductances of the exterior circuit are indicated as L³, L⁴. Any suitable artificially cooled coil is shown at O and a crucible 90 or other container or resistor to be heated is inclosed by the coil.

In Fig. 2, complying with the statute, I have indicated one means of carrying out my invention, but without any intention 95 of restricting to this means and in fact with knowledge that the artificial cooling may be applied to any form of high frequency coil, external to either a solid or hollow conductor or within a hollow conductor and by any 100 system of artificial cooling suitable to the type or shape of coil or the character, section, material, location or use of coil conductor to which it is to be applied.

With this explanation, I will proceed to 105 describe the form shown in Fig. 2:—

The base 1 is apertured at 2 for convenient withdrawal of the parts and the aperture is normally closed by a slide 3. Upon this base I rest a cylinder 4, within which is 110

placed a highly resistant sand 5 or other filling material extending to any height 6 corresponding with the intended lower limit of the melt.

5 A refractory cylinder 7' is then put in place to hold the material 8 to be melted or treated against lateral flow, and sand or other highly refractory supporting and heat insulating material is sifted in about the cylinder.

10 In Fig. 1 the cylinder 7 is shown as having a closed bottom at 7², as may be desired if it be a crucible intended to pour from the top. Either the cylinder or a crucible, so used, may be electrically conducting, where it is to form the resistor to heat an electrically conducting or non conducting content, or electrically non-conducting where the current is to be induced in an 20 electrically conducting (resistor) content.

15 A cap 7³ may be used if desired but has not proved necessary in the attainment of temperatures sufficient to melt highly refractory metallic oxides and metals.

20 The conductor forming the coil O' is hollow, but, whether solid or hollow may be of any section. It is here shown as extending from 9, where the refrigerant enters, to 10, where it discharges, and of elliptical section, edgewise-wound as shown at 11. Where the conductor is hollow it may be supplied with any cooling content 12, such as air, oil, water, salt solution, carbon dioxide, ammonia, etc., from any source of 30 fluid or vapor supply desired. A liquid refrigerant possesses many advantages.

35 Where an electrically non-conducting internal cooling medium is used the conductor may be insulated at both ends by a non-conducting length, such as rubber, effectively insulating the applied electrical current supply.

40 If a conducting liquid be used as the supply, it is desirable to break the circuit in a different way, at one or at both ends, as by insulating the source of liquid supply and discharging the liquid in the form of a spray as at 10, with sufficient drop to break the conducting continuity of the spray. As 45 a precaution I have shown the spray in Fig. 2, though the resistance of the water there used would probably form sufficient insulation.

45 The high frequency electric current, whether from a special generator or obtained by oscillatory discharge of condensers, is applied to the coil at 13, 14 or 13', 14' from a source of high frequency supply 50 15, 16 or 15', 16', which may be directly generated or represent the oscillatory discharge from condensers and, correspondingly, may vary widely in voltage. For a resistor of circular section the helical form of coil shown is desirable. This may be greatly 55 varied.

Where the cooling medium is to be applied to the exterior of the high frequency coil, it is undesirable to use a conductor of hollow section because it reduces the number of turns per unit length. In Fig. 3 a coil of 70 flat conductor 11', edgewise wound, is shown with an exteriorly applied cooling medium in the space 17 between walls 18, 18'. It may have either inlet or discharge at 19, the other not being shown, with forced or 75 natural thermal circulation as preferred.

80 All of the other parts shown are preferably of highly refractory material whose form and composition will be dictated by convenience of the necessities of the intended use. Excellent results have been obtained using quartz for the outer cylinder and clay for the inner cylinder and a fine silica (silex) sand between. This gives the carbon-free heating conditions so much 85 sought in high temperature melting and treating, especially with the ferrous metals. For the higher temperatures such as are required for melting platinum I substitute zirconia sand for the silex sand used with 90 lower temperatures and with a temperature elevation obtained limited by no other consideration than the heat resistance of the materials holding the melt.

95 In operation, with the form shown, the slide is placed in position, sand is sifted within the outer cylinder to the desired height before the inner refractory cylinder is placed in position and then about the inner cylinder to approximately its upper 100 level. The material to be melted or heat-treated is then inserted, the cooling medium applied and the high frequency electric current connected. The pressure or character 105 of the cooling medium may be increased or changed for the higher temperatures.

With normal water pressures and a comparatively small coil section, temperatures over 2500° C. have been attained in a cylindrical resistor mass not more than one and 110 one half inches less in diameter than the exterior of the inducing coil, whose temperature was lower than that of the room. The prospect of exceeding the temperature of the electric arc by my present invention is 115 quite promising.

I have also melted ferrous metals and their alloys free from carbon or other elements which might even slightly affect their 120 purity, and could melt them directly in the sand without using any container where the clay, magnesia, zirconia or other cylinder 7 is shown. The material to be melted defines a pocket or form in the sand which is occupied by the melt. The sand forms a heat insulator and mold and, at sufficiently high temperatures, with the particular sand chosen, melts close to the material melted, and separately or in chemical union with the material melted subsequently chills 125 130

about it forming an inclosing shell. This mold-forming property of the sand causes it to heal any breaks in the cylinder or crucible where one is used, without interruption 5 to the process.

By the method of heating described, inducing current directly within an electrically conducting material (resistor) with artificial cooling of the inductor coil in a 10 crucible free from carbon, where desired, I have not only succeeded in melting many metals and metallic oxides requiring high temperatures and without reduction of the oxides but have been able to control the conditions under which the melting took place. 15

Among the metals melted have been electrolytic iron, electrolytic nickel, aluminum, molybdenum and platinum.

Alloys of pure metals requiring high 20 temperatures have been made by me alloying such metals as iron and copper, iron and molybdenum and molybdenum and copper in different proportions.

Among the oxides which I have melted 25 are oxides of chromium, iron, cobalt and nickel. I prefer to use a crucible for this.

I have also used the furnace for coating purposes as, for example, in the coating of 30 the walls of a graphite container with a carbide by covering the walls with a coating of oxid—such as the oxid of aluminum and melting it in place to form the carbide as a coherent, continuous protective coating.

Having thus described my invention, what 35 I claim as new and desire to secure by Letters Patent is:—

1. An artificially-cooled inductor furnace coil for electric inductive heating purposes, in combination with a source of high frequency current.
2. An artificially-cooled inductor furnace coil for electric inductive heating purposes, free from interlinkage with transformer iron.
3. An artificially-cooled inductor furnace coil for electric inductive heating purposes free from interlinkage with transformer iron, in combination with a source of high frequency current supply.
4. A hollow inductor furnace coil for electric inductive heating purposes free from interlinkage with transformer iron, in combination with a source of high frequency

electric current supply and a cooling medium applied to the interior of the hollow 55 coil.

5. A hollow inductor furnace coil, for electric inductive heating purposes, in combination with a cooling medium applied to the interior of the coil and sprayed therefrom at one end for insulation purposes. 60

6. A hollow inductor furnace coil, for electric inductive heating purposes, in combination with a cooling medium applied to the exterior of the coil. 65

7. A hollow inductor coil of oval section, edgewise-wound.

8. A hollow inductor furnace coil of helical form adapted to surround the material to be heated, a cooling medium applied to 70 the coil, and high frequency current passed through the coil.

9. A furnace comprising a coil, a support for the coil, a refractory container for the melt and a finely divided refractory material about the container, adapted to heal breaks therein, in combination with high frequency current supply therefor. 75

10. A high frequency inductive electric furnace utilizing a finely divided loose refractory to hold the melt. 80

11. A high frequency inductive electric furnace having a refractory shell limiting the melt laterally and a loose refractory bottom for the shell. 85

12. The process of carbon-free heating of materials, which consists in placing them within a carbon-free refractory and developing the heat directly within them by electric induction while they are so placed. 90

13. The process of heating materials which consists in utilizing the material to be heated, to define the mold for the melt within a finely divided refractory and inducing a current in the material as there 95 placed.

14. The process of melting materials requiring a high temperature, which consists in inclosing the materials within a conductor in inductive relation thereto, artificially cooling the conductor to reduce its resistance, improve its insulation and permit closer coupling, and passing a high frequency electric current through the conductor. 100

EDWIN F. NORTHRUP.
